DESIGN FOR A FLOOR POLISHER

Eldred J. Vetter, Whitefish Bay, Wis., assignor to
S. C. Johnson & Son, Inc., Racine, Wis., a corpora-
tion of Wisconsin

Application November 14, 1940, Serial No. 96,576

Term of patent 14 years

To all whom it may concern:

Be it known that I, Eldred J. Vetter, a citizen of the United States, residing at Whitefish Bay, in the county of Milwaukee and State of Wisconsin, have invented a new, original, and ornamental Design for a Floor Polisher, of which the following is a specification, reference being had to the accompanying drawing, forming part thereof.

Fig. 1 is a side elevational view of a floor polisher showing my new design;

Fig. 2 is a top plan view thereof with the yoke

in lowered position and with the handle omitted for convenience of illustration;

Fig. 3 is a front elevational view of Fig. 2 but with yoke in raised position; and

Fig. 4 is a rear elevational view of Fig. 3.

The dominant feature of my design resides in the portion shown in full lines.

I claim:

The ornamental design for a floor polisher, as shown and described.

ELDRED J. VETTER.
